UNITED STATES PATENT OFFICE.

SAMUEL M. LONGLEY, OF HUDSON CITY, NEW YORK.

IMPROVEMENT IN HOISTING-MACHINES.

Specification forming part of Letters Patent No. 41,779, dated March 1, 1864.

To all whom it may concern:

Be it known that I, SAMUEL M. LONGLEY, of Hudson, of Columbia county, in the State of New York, have invented certain new and useful Improvements in Hoisting-Machines; and I do hereby declare that the following is a full and exact description thereof, reference being had to the accompanying drawings, making part of this application.

My invention relates to an improved apparatus or machine for hoisting, and has for its object to provide a combination of mechanical devices which shall constitute a machine better adapted to the economical application of power for lifting heavy weights than any now known, and one which shall be simple and capable of being readily employed under varying circumstances; and to these ends my invention consists in the employment, in combination with two chain-wheels, or their equivalents, of different diameters and a chain of a system of gearing, substantially as hereinafter fully described.

To enable those skilled in the art to make and use my invention, I will now proceed to describe the construction and operation of one of my improved machines, referring by letters to the accompanying drawings, forming part of this application, and in which—

Figure 1 is a side elevation of my improved hoisting-machine, and Fig. 2 is an edge view of the same.

Similar letters indicate similar parts in the different figures.

A is the frame of the machine, in which are mounted two shafts, *a* and *b*, one of which, *a*, I make fast in the frame A, the other, *b*, to turn in bearings formed in said frame. On the shaft *a* are hung, so as to turn freely, two chain-wheels, *c* *d*, of ordinary construction, and adapted to receive in their peripheries the links of a chain, B, and on said shaft *a* is also hung a gear, C. The gear C and chain-wheels *c*, *d* I propose to make all in one piece or solid, and the whole to turn freely on shaft *a*. On the shaft *b* are keyed (inside of the frame A) a pinion, D, and (outside of said frame) a rope-wheel, E. The pinion D meshes into and drives the gear C, which carries with it the double chain-wheel *c* *d*. The chain B passes over the pulley *c*, thence down and

around an ordinary sheave-block F; thence over the pulley *d*, and then has its ends joined.

The operation would be the same without uniting the ends of the chain, the only object of which is to shorten the amount of chain requisite to lift a given distance.

The wheel E is provided with a rope, G, which is of the proper size to fit into the forked ends of the arms of said wheel, and of a suitable length to operate the machine where it may be located. It will be understood that, if a weight be attached to the block F and power applied to rope G to pull the latter in the direction indicated by the arrow, the pinion D will drive the gear C, which, carrying with it the double chain-wheel *c* *d*, will cause the chain to move as indicated by arrows; but since the diameter of the portion *c* is greater than that of *d*, it follows that the chain B will be taken up by *c* faster than it is let out (or down) by *d*, the consequence of which is the elevation of block F, (carrying the weight to be raised,) and it is clear that at each revolution of the chain-wheels *c* *d* the block F will be elevated a distance equal to the difference between the circumferences of *c* and *d*.

It will be seen that thus a very simple and effective hoisting-machine is produced.

I do not wish to limit myself to the precise form shown of any of the parts in carrying out my invention. The gears D and C may be varied in proportions to change the speed of the machine to adapt it to different kinds of work.

I do not claim any of the elements of the machine, as they are each and all, as elements, very old and well known; but

What I do claim as new, and desire to secure by Letters Patent, is—

The employment of the double chain-wheel *c* *d* with a chain, B, in combination with a system of gearing, C D, and a suitable power-wheel, E, substantially as and for the purposes described.

SAMUEL M. LONGLEY.
